METHOD OF AND APPARATUS FOR FORMING PATCHES

Filed July 7, 1930.

UNITED STATES PATENT OFFICE

1,941,019

METHOD OF AND APPARATUS FOR
FORMING PATCHESWilber P. Peterson, Kansas City, Mo., assignor
of one-half to Snyder and Gray Incorporated,
Kansas City, Mo., a corporation of Missouri

Application July 7, 1930. Serial No. 465,992

4 Claims. (Cl. 164—29)

My invention relates to a method of forming tire patches or the like and apparatus for carrying out the method, having reference more particularly to patches of flexible material including 5 rubber which require beveled edges and which ordinarily are beveled by skiving or slicing action of a knife on the periphery of a patch after the same has been cut from a sheet of material.

The principal objects of my invention are to 10 confer beveled edges on patches by the operation that cuts the patches from a sheet of material, and to support portions of a sheet of material in such a position that operation of a cutting out or punching tool will confer a thin edge on a 15 patch, whereby production of beveled edge patches may be facilitated, and patches having thin edges may be produced cheaply and rapidly.

In accomplishing these and other objects of 20 my invention, I have provided improved details of structure, the preferred forms of which are illustrated in the accompanying drawing, wherein:

Fig. 1 is a side elevation partly in section of apparatus adapted for carrying out my improved 25 method of producing patches, a motor for actuating the apparatus being shown fragmentarily.

Fig. 2 is a front elevation of the device partly in section.

Fig. 3 is an enlarged detail perspective view of 30 a punch and a ram shown fragmentarily.

Fig. 4 is a fragmentary section through the die and punch in material-distorting position for applying the cut.

Fig. 5 is a perspective view of a patch formed by my improved method.

35 Referring in detail to the drawing:

1 designates a base or bed plate adapted to support a die 2 presently described, and 3 a frame mounted on the base at one side thereof and integral therewith, having a bearing 4 at its upper 40 end for supporting a shaft 5 having a pulley 6 provided with a V-shaped peripheral groove. A belt 7 shaped to engage in said pulley groove moves on a similar pulley 8 driven by a motor 9 for rotating the shaft. A crank 10 on the shaft 45 has a crank pin 11 on which is mounted a link 12 pivotally connected with a plunger or ram 13 reciprocating in a guide 14 projecting from the frame and adapted to support a punch 15 having a peripheral cutting edge 16 enclosing an area 50 corresponding approximately to the size of a blank to be produced by the apparatus and defining the pattern of the blank.

The die 2 is fixed to the base below the punch, and has an orifice 17 forming a peripheral knife 55 edge affording slight clearance for the edge of

the punch whereby the punch may cut a blank from a sheet of material mounted on the face of the die.

In order to confer thin and preferably beveled edges on the blank as the same is cut out by the 60 punch, I provide a boss-like face member or pad 18 on the end face of the punch having sides spaced inwardly from the cutting edge 16 thereof and preferably having beveled or rounded edges 19 to avoid damage to the patch. The middle 65 portion of that area of the sheet which is to be cut out to form a blank will be depressed by the pad into the orifice of the die in advance of the punch edge and be retained therein while the edge of the punch acts cooperatively with the die 70 to sever the blank from the sheet.

The pad preferably consists of a separate plate 75 conforming in contour to the pattern of the punch edge and die orifice, having openings 20 to receive studs 21 formed on the punch face and an axial opening 22 for admitting a retaining screw 23 or the like into the punch for securing the pad to the punch.

The pad as illustrated in Fig. 4 produces a fullness or puckering effect in the area of material 80 pressed into the die opening, wherein the middle portion 24 of said area engaged by the pad and depressed thereby is connected to the surrounding material located on the die face by an annular or marginal strip or border 25. The border strip 85 inclines upwardly outwardly from said portion 24 to the margin of the blank defined by the edges of the punch and die, and is thus retained in angular position relative to the supported material and the cutting edges and free from contact 90 with the pad while the punch operates.

The punch edge thus passes angularly through the material, to effect a bias cut, and severs all portions of the blank edge simultaneously, to produce the beveled edge on the blank as shown in 95 Fig. 5.

In forming tire patches, a sheet may be employed having a body formed of resilient or flexible material such as rubber, and having a relatively inelastic fabric or like facing such as linen 26 on 100 one side to protect an adhesive face of the body. Such a sheet is fed to the machine with the uncovered face of the body on the die. The pad will then bear on the facing to depress the blank forming area, drawing portions of the body and facing from the area thereof surrounding the orifice, and distorting and moving said portions into the orifice to add to the area defined by the face of the pad. The added portions comprise edges of 105 the blank-forming area located at an angle to 110

receive the punch and effect the production of the bevel edge on the patch.

The base is provided with an opening registering with the die orifice into which the finished 5 beveled patches will fall and collect.

The opening 27 may conduct the finished patches to a pan 28 located in a recess 29 in the lower end of the base.

In using the invention, a die and a punch may 10 be made of any desired shape and size to form a patch having desired pattern and dimensions, and the bevel-forming pad may have edges spaced from the edges of the punch and have suitable thickness to depress a portion of the sheet of material sufficiently to effect formation of desired 15 type of thin edge on the patch. The material may be fed by any suitable means along the die beneath the punch, at a rate corresponding to the rate of reciprocation of the ram.

20 Formation of beveled patches by a single stamping operation in apparatus as described, permits rapid production of finished patches, and as many as 350 patches per minute may be produced, contrasting with the slow production of 25 patches which require movement of a knife around the periphery of a blank to form the beveled edge.

Ability to produce patches of any desired shape and provided with beveled edges thus promotes 30 economy in the use and production of patches, since patches may be supplied to exactly suit a particular situation, for example, a particular type of wound in a tire or tube, and the shape of die edges need not be arranged circularly or according to any arbitrary design merely to facilitate skiving by supplemental means. Straight 35 sided patches are further possible with the use of my method and apparatus, whereby maximum economy in use of the material in a sheet is afforded, thus avoiding the wasteful practice of 40 cutting arcuate edge patches from a sheet.

What I claim and desire to secure by Letters Patent is:

1. An apparatus for forming patches of resilient material having a relatively non-elastic facing, including a die member having cutting edges arranged to form the required shape of the patch, a punch member having cutting edges cooperating with said cutting edges on the die member, 50 and a pad member fixed to the lower face of the punch member and arranged to displace the central portion of the material forming the patch prior to engagement of the cutting edges for drawing the patch material at an angle across 55 the cutting edges and said pad member having its peripheral side edges spaced inwardly relative

80

tively to said cutting edges to provide an annular recess about the pad wherein the material adjacent the cutting edges puckers without loosening the non-elastic facing from the resilient material of the patch during the cutting operation.

85

2. An apparatus for forming patches of resilient material having a relatively non-elastic facing including a die member provided with an opening similar in shape to the patch to be formed and having cutting edges surrounding said opening, a punch member projectable through said opening and having cutting edges cooperating with said cutting edges on the die member, and a pad member on the lower face of the punch member and having a peripheral bevelled edge spaced downwardly and inwardly from the cutting edges of the punch member to displace the central portion of the patch for drawing the patch material across the cutting edges at an angle substantially equal to the angle of said bevelled edge and forming an annular recess about the pad wherein the material adjacent the cutting edges puckers without loosening the non-elastic facing from the resilient material forming the patch during the cutting operation.

90

95

3. An apparatus for forming patches of resilient material having a relatively non-elastic facing including a die having cutting edges, a punch member having cutting edges cooperating with the edges of said die member, and a pad member on the punch member for displacing the central portion of the patch to draw the patch material at an angle across the cutting edges and having its peripheral side edges spaced inwardly from the cutting edges of the punch member a distance greater than the thickness of said patch-forming material to provide a peripheral recess wherein the material adjacent the cutting edges puckers and adjusts itself upon cutting operation of said die and punch members to prevent 100 loosening of the facing from the resilient material.

105

110

115

4. The method of forming patches from a sheet of resilient material having a relatively non-elastic facing comprising applying pressure to the central portion of a patch-forming area of the sheet to displace said area from the plane of the sheet, confining the pressure only to the central portion of said area whereby the marginal portion of the area is free from pressure and resulting in 120 the marginal portion puckering upwardly adjacent the pressure area thus preventing loosening of the facing from the resilient material, and cutting the sheet at the periphery of said marginal portion.
